CLAIM

The ornamental design for a dual frame display for a display screen, as shown and described.

DESCRIPTION

FIG. 1 is a front view of a dual frame display for a display screen; and,

FIG. 2 is a front view of a second embodiment thereof.
The broken line drawings of a display screen and the
portions in the screen are for illustrative purposes only and
form no part of the claimed design.

1 Claim, 2 Drawing Sheets

FIG. 1

FIG. 2
